[57] CLAIM

The ornamental design for a shower escutcheon handle, as shown and described.

DESCRIPTION

FIG. 1 is a perspective view of a shower escutcheon handle showing our new design;

FIG. 2 is a front elevational view thereof;

FIG. 3 is a top plan view thereof;

FIG. 4 is a bottom plan view thereof;

FIG. 5 is a left side elevational view thereof; and,

FIG. 6 is a right side elevational view thereof.

The broken line showing of the shower escutcheon in FIGS. 1-6 is for purposes of illustration only and forms no part of the claimed design.
